UNITED STATES PATENT OFFICE.

UMBERTO PUGLIESE, OF ROME, ITALY.

PROTECTING STRUCTURE FOR SHIPS.

1,299,026.

Specification of Letters Patent.

Patented Apr. 1, 1919.

Application filed July 5, 1917. Serial No. 178,780.

To all whom it may concern:

Be it known that I, UMBERTO PUGLIESE, a subject of the King of Italy, residing at Rome, Italy, have invented new and useful 5 Improvements in Protecting Structures for Ships, of which the following is a specification.

This invention relates to means for protecting the hulls of ships and vessels from 10 being damaged by the impact or explosion of torpedoes or submarine mines of the kind in which chambers or tanks are provided along each side of the hull, such chambers serving to absorb the energy of the explosion. 15

According to this invention, the protective device comprises the provision at each side of the ship of one or more shells or tanks inclosed within a single surrounding 20 shell or tank. By such an arrangement when an explosion occurs it is the inner tank or tanks that principally absorb the energy of the explosion gases by partly or wholly collapsing while the outer surrounding 25 shell may be ruptured only locally.

The invention will now be described with reference to the accompanying drawings which illustrate by way of example one embodiment of the invention and in which,

30 Figure 1 is a cross vertical sectional view of the protecting structure or tank.

Fig. 2 is a horizontal sectional view, on the line A—A of Fig. 1, of a portion of the said structure.

35 Fig. 3 is a transverse vertical section of a ship specially constructed in view of the adaptation thereto of the protecting device forming the object of the present invention; and

40 Fig. 4 shows one of the ways for transforming the ship to the normal and usual construction, when the necessity for the protecting device ceases.

The ship constructed according to the present invention must be built in cross section as shown in Fig. 3, that is, with inwardly extending curved sides *a*, forming, in its central part below the water line, the recesses *e*, in which recesses the structure or tank illustrated in sectional views in Fig. 1 and Fig. 50 2, is fitted and firmly supported in a convenient manner, at each side of the ship. Such tank is formed by an external structure *b*, circular or of other form in cross section, which constitutes a longitudinal tank having in its interior a chamber or chambers *c*. The space

between the external structure and said internal chamber or chambers is filled up with any liquid substance such as salt water, oil or the like, while the internal chamber or 60 chambers will be left vacant or filled up with an extremely compressible substance having a very low density such as cork and the like.

Obviously, the protecting structure will 65 be conveniently made with strengthening frames and longitudinally divided into sections by means of water proof partitions, in the well known manner.

The construction of the ship for employment with the above described system of protecting tanks according to the present invention can be constituted as follows (Fig. 3):

(1) By a simple or double bottom *d*; 75

(2) By the side walls which may be strengthened on the outside by an additional layer of iron sheeting and inside by convenient cellular structures;

(3) By a series of strong transverse duly 80 reinforced beams and partitions;

(4) By a closing wall of iron sheeting following the same curvature as the protecting tanks which may, if necessary, be used. 85

The upper part of the ship structure will be completed by a bulwark with the decks and the superstructure according to the kind of cargo which the ship is to carry, and completed fore and aft by structures imparting to the ship the usual contour lines, these fore and aft parts being reduced to the least possible size and either partly protected or filled with a material of small density or with cargo. 90 95

Should an explosion take place on the under water side of a ship protected as above specified, the exposed part of the surrounding tank may be deformed or broken, while the internal part immediately next to the ship's hold will be protected from damage but the main damage will be concentrated upon the inner tank or tanks *c* which will more or less collapse. The flooding of water will therefore be reduced to a limited space 105 in the internal device corresponding to the initially empty space, the ship's hold remaining consequently fully safeguarded.

Fig. 3 represents an example of the midship structure of a cargo boat for which the 110 water line at full cargo is made to coincide with a plane tangent to the upper surface

of the outer protecting tanks. The inner and outer tanks are represented in the drawing as being perfectly cylindrical and circular in their cross section, but they may be 5 made of any other convenient form.

The construction of a ship made according to the present invention will have the following characteristics.

(1) A guarantee against underwater 10 lateral explosions, the weight of the protecting structures or tanks being confined within moderate limits;

(2) The dead weight capacity is only 15 lightly, and in some cases, not at all reduced;

(3) An increase of cargo space in the 20 ship's hold in comparison with other types of protection, as the protecting tanks may be utilized, on a large scale, for shipping goods or liquid fuel;

(4) As the flooding in case of an explosion is reduced to a minimum, the trimming of the ship will not be substantially interfered with.

(5) The simplicity of said protecting structures or tanks and consequently of their 25 design and construction as well as of their setting up and the easy distribution of the joints of the iron plating afford to the building up of the said protection system a characteristic of rapidity and economy; (6) once 30 the reasons which render the underwater protection necessary cease, said protecting structures or tanks may eventually be removed and the ship easily transformed into 35 an almost normal type and form of vessel (Fig. 4);

(7) When said transformation has been 40 effected the protecting structures or tanks may be easily utilized for other obvious purposes, so that practically no loss of material takes place.

The protecting structures which form the

principal object of the invention may be applied to some types of already built cargo- 45 boats by means of convenient internal adaptations of the structures of the ship hold in order to fix the said protecting tanks in position.

I claim:—

1. Means for the protection of vessels, comprising a fluid holding shell extending alongside the hull, and compressible shock absorbing means of low density contained within said shell. 50

2. Means for the protection of vessels whose hulls are provided with an exteriorly lengthwise extending recess, said means comprising a fluid holding shell seated in said recess, and compressible shock absorbing 60 means of low density contained within said shell.

3. In protecting means for vessels, the combination, with a ship's hull, having exterior recesses, extending lengthwise, at opposite sides thereof, of a fluid containing cylindrical shell seated in each recess, and compressible shock absorbing means, of low density, also contained within said shells. 65

4. In protecting means for vessels, the combination, with a ship's hull, having concave recesses extending lengthwise exteriorly thereof, of a fluid containing outer cylindrical shell seated in each recess, and an inner shell inclosed by each outer shell, in 70 spaced relation therewith, the inner shell containing compressible shock absorbing material, and being more susceptible to rupture than the outer shell. 75

In testimony whereof I have signed my 80 name to this specification in the presence of two subscribing witnesses.

UMBERTO PUGLIESE.
